REMOVABLE CONDUIT HOUSING

Gustave J. Soderberg, Babylon, N. Y.

Application March 28, 1944, Serial No. 528,423

1. Claim. (Cl. 138—75)

The present invention relates to a locking and removable conduit housing for conduits such as electric wires and cables and water, steam and gas pipes.

One of its objects is to provide a housing for the conduits named which may be affixed like molding to the wall or to the floor.

Another object is to provide a housing for such conduits, which may be installed without disconnecting the conduits.

A further object is the provision of a housing for electric wiring which may be acceptable to the fire underwriters.

A still further object is the provision of locking and unlocking means for such housing.

These and other objects may be attained by providing a housing comprising four simple parts; a base plate to affix to the wall or floor; one or more brackets to be affixed to the plate; a channel shaped cover to fit over the brackets; and a locking stud to engage the brackets through the cover.

Preferred embodiments of the invention are illustrated in the accompanying drawings in which—

Figure 1 is a transverse section of the entire housing, said view being a view on the line 1—1 of Figure 2.

Figure 2 is a longitudinal section of the entire housing, showing how adjoining lengths of the housing are joined;

Figure 3 is a perspective view of the cover portion of the housing, showing how adjoining lengths thereof are joined;

Figure 4 is a perspective view of the plate portion of the housing, showing the bracket portions, also in perspective, affixed thereto.

Figure 5 is a perspective view of the locking stud portion of the housing;

Figure 6 is a section on the line 6—6 of Figure 1, showing the socket portion of the brackets which receives the locking stud portion;

Figure 7 is a perspective view of said bracket socket portion;

Figure 8 is a transverse section of another embodiment of the invention, said view being a view on the line 8—8 of Figure 9;

Figure 9 is a longitudinal section of the embodiment shown in Figure 8;

Figure 10 is a perspective view of the plate portion of the embodiment shown in Figure 8; and

Figure 11 is a perspective view of the bracket portion of the embodiment shown in Figure 8.

Referring to the embodiment shown in Figures 1 to 7 inclusive of the drawings, the housing con-

struction comprises a base plate 15, a bracket 16 affixed thereto, a channel shaped cover 17 mounted on said bracket, and a locking stud 18 engaging said bracket through said cover, and locking said cover to said bracket.

Base plate 15 comprises an elongated, rectangular shaped body 19 made, preferably, of metal, but which may also be made of plastic or any other similar material. Body 19 may be made in any width, length and thickness. It is suggested however, that it be made in varying widths, such as 2, 3, 4 and 5 inch widths. For certain purposes body 19 may have a width of a foot and may even be made wider than that. A standard length 15 of 6 or 8 feet is suggested, and a thickness corresponding to the thickness of moderately heavy sheets of sheet metal. Body 19 may have small holes 20 formed in it at spaced intervals. Plate 15 is placed flat against the floor 21 near the wall 22 or against the wall near the floor or elsewhere and affixed thereto by means of screws 22.

Bracket 16 comprises a substantially U shaped body 23 consisting of two leg portions 24 and 25 joined at one end by means of yoke 26, said leg portions having inwardly tread foot portions 27 and 28 at the other end. Foot portions 27 and 28 lie in a common plane which is parallel to the plane in which yoke 26 is disposed. Leg portions 24 and 25 are parallel to each other and substantially perpendicular to yoke 26 and foot portions 27 and 28.

Yoke 26 has a circular depression 29 formed in it, approximately midway between leg portions 24 and 25, said depression having a transverse raised portion 30. In the center of said circular depression 29 and cutting across said raised portion 30, is a substantially rectangular aperture 31, longitudinally disposed with respect to the yoke 26.

Bracket 16 may be made either of metal or of plastic material, but preferably of metal having a thickness substantially equal to the thickness of the base plate 15. As is clearly shown in Figures 1 and 4, bracket 16 is affixed transversely to base plate 15, its foot portions 27 and 28 in contact with, and either welded or riveted to said base plate, its leg portions 24 and 25 lying in a plane, respectively, with side edges 32 and 33 of said base plate. From this description it is apparent that the length of bracket 16 is 45 substantially equal to the width of base plate 15. There may be as many brackets 16 to each base plate 15 as may be found desirable. It is suggested that brackets 16 be spaced at intervals of 2 feet.

Channel cover 17 comprises an elongated sub-

stantially U shaped body 34 having shape and dimensions enabling bracket 16 as affixed to base plate 15 to nest within it. Midway between its legs 35 and 36, and at regular intervals throughout its length (which corresponds to the length of base plate 15) are apertures 37 having downwardly beveled edges 38. Cover apertures 37 are intended to register with bracket apertures 31. There are therefore at least as many cover apertures 37 as there are brackets 16 and bracket apertures 31. At one end of each length of channel cover 17 is a raised, stepped portion 39 which is intended to receive telescopically the opposite end 40 of an adjoining length of channel cover 17.

Channel cover 17 may be made either of metal or of plastic material, but preferably of metal. The same type of sheet metal out of which base plate 15 is intended to be made, will suffice for channel cover 17.

Locking stud 18 comprises a beveled head 41 having a screw driver receiving slot 42, a stem portion 43 and a transversely elongated, rectangular base portion 44. Base portion 44 has a beveled end portion 45 and a rounded surface 46 facing the beveled head 41.

The beveled head portion 41 corresponds in shape and dimensions to the beveled channel cover apertures 37. The rectangular base portion 44 corresponds in shape and dimensions to the bracket apertures 31. The rounded surface 46 of rectangular base portion 44 corresponds in shape and dimensions to the hollow portion 47 which is formed underneath raised portion 39 of bracket 16. There are as many locking studs 18 as there are brackets 16 and channel cover apertures 37.

The embodiment of the invention shown in Figures 8, 9, 10 and 11 is in all respects identical with the embodiment shown in Figures 1 to 7 inclusive, except in the following particulars:

Base plate 48 as shown in Figures 8 and 10 has upturned and then inwardly turned side edges 49 and 50. Bracket 51 has inwardly turned, and then downwardly turned and then outwardly turned leg ends 52 and 53. The bracket 51 may be made of spring steel. The grooves 54 and 55 which are thus formed in leg ends 52 and 53 are adapted to receive base plate edges 49 and 50. Bracket 51 is affixed to base plate 48 simply by squeezing leg ends 52 and 53 together and then allowing them to spring outwardly to engage base plate edges 49 and 50.

The invention may be used in the following manner, referring now to the embodiment shown in Figures 1 to 7 inclusive.

The base plate 15 to which brackets 16 are affixed, is fastened to an appropriate place such as the floor 21. Wires or cables 56 are now drawn through brackets 16 and connected in the usual manner. Channel cover 17 is then placed over brackets 16 in such manner that its legs 35 and 36 straddle brackets 16 and reach floor 21 immediately adjacent both long edges 32 and 33 of base plate 15. Locking studs 18 are now inserted into and through channel cover apertures 37 and bracket apertures 31. A screw driver 15 is then used to turn locking studs 18 one quarter of a turn until their rounded surfaces 46 fall into hollow portions 47 of brackets 16. The heads 41 of locking studs 18 will now be flush with the outer surface of channel cover 17. The invention is now installed.

The embodiment shown in Figures 8 to 11 inclusive may be installed around wires 56 even though these wires may be fully connected at both ends. This may be done as follows:

Base plate 48 is inserted under wires 56 longitudinally with them. It is then fastened to floor 21 as above described. Brackets 51 are now sprung into engagement with base plate edges 49 and 50. The channel cover and locking studs are then installed in the manner outlined above.

It is apparent that the specific illustration shown has been given by way of illustration and not by way of limitation and that the structure above described is subject to a wide variation and modification without departing from the scope or intent of the invention, all of which variations and modifications are to be included within the scope of the present invention.

40. What is claimed is:

In a housing construction for conduits, a bracket comprising a substantially U shaped body consisting of a yoke and two elongated leg portions, said leg portions having inwardly turned, then downwardly turned and then outwardly turned end portions, said yoke having a circular depression formed in it midway between said leg portions, a transverse raised portion formed in said circular depression, and a rectangular aperture formed in said circular depression, cutting across said raised portion.

GUSTAVE J. SODERBERG.
